Mfg.

UNITED STATES PATENT OFFICE.

RICHARD SCHEIBE, OF KLOTZSCHE, GERMANY.

RAILWAY SUPERSTRUCTURE.

Application filed May 12, 1923. Serial No. 638,496.

To all whom it may concern:

Be it known that I, RICHARD SCHEIBE, a citizen of the Free State of Saxony, residing at Klotzsche, Saxony, Republic of 5 Germany, have invented certain new and useful Improvements in Railway Superstructures, of which the following is a specification.

This invention relates to railway roadbeds and has for its principal object to provide a new and improved construction of a tie or sleeper by the use of which the rapid deterioration of the roadbed experienced with the types of sleepers now generally 10 employed is substantially overcome and consequently a large proportion of the burdensome roadway maintainance costs are therefore saved.

In order to accomplish this very desirable 20 object, I provide a sleeper having a cross sectional profile such that the sleeper under the influence of the external forces applied to it is enabled to yield elastically and alter its form which alterations in the profile of 25 the sleeper are transmitted, along lines normal to the various points of the profile, to the supporting roadbed or ballast in such a way as to distribute or disperse the shocks or forces over a wide supporting area, close 30 to the rails, thus avoiding the objectionable localization of the forces communicated to the supporting roadbed along restricted areas which with the ties or sleepers in common use are substantially equal to or 35 but slightly greater than the horizontal cross sectional area of the tie or sleeper itself. This localization of the forces adjacent each sleeper obviously causes inequalities and bends in the rails according to the 40 differences in the nature and composition of the supporting subsoil.

Considered therefore, in its more specific aspects, the object of this invention is to provide a tie or sleeper having such a construction that it will be permitted to yield and so alter its shape momentarily that the shocks or forces to which the rails are subjected will be dispersed or distributed over a continuous supporting area at a very low 50 depth from the rail.

Another object is to provide a means for attaching the rail to the sleeper so that a substantially rigid and permanent connection is afforded whereby all the forces exerted by the rail whatever their direction 55 are transmitted by the rail undiminished

and with full strength to the sleeper to be absorbed thereby.

While I am aware that many types of sleepers having elastic properties have been 60 proposed, attention is called to the fact that mere elasticity of the sleeper is not sufficient to accomplish the desirable result of distributing or dispersing the shocks, but that in addition to the elasticity the sleeper must 65 possess certain other attributes particularly as to the shape of the surfaces upon which it rests upon the earth works.

A further object of this invention is 70 therefore, to provide a sleeper having a proper shape of supporting surfaces and which is also of hollow construction thereby permitting it to be manufactured at a comparatively low cost while at the same time permitting the interior of the sleeper 75 to be filled with suitable ballast to attain a high moment of inertia.

For the accomplishment of these and such further objects as will hereinafter be apparent to those skilled in the art to which 80 this appertains, the invention consists in the construction, combination and arrangement of parts herein specifically described and illustrated in the accompanying drawings, 85 wherein is shown a preferred embodiment of the invention, but it is to be understood that changes, variations and modifications may be resorted to which fall within the scope of the claims hereunto appended.

In the drawings forming a portion of this 90 specification:—

Fig. 1 shows an enlarged cross section or profile of the sleeper.

Fig. 2 is a diagrammatic view showing the manner in which the shocks and forces 95 received by the rail are transmitted through the sleepers and distributed thereby over a continuous supporting area.

Fig. 3 is a partial top view of the sleeper.

As shown in Fig. 1 of the drawing, a preferred form of a sleeper embodying my invention comprises the plane upper middle part 10, on which the foot or base of the rail 11 rests.

The plane middle part 10 of the sleeper 105 merges into the side walls 13 which are of substantially cylindrical shape and extend a distance approximately equal to or slightly less than 65° of a circle starting from the point where the plane upper wall terminates. At their lower extremities the cylindrical side walls 13 merge into plane sec- 110

tions 14 substantially tangent to the lowest points of the cylindrical side walls and extending downwardly therefrom preferably at an inclination of 1:4.

5 By referring to Fig. 2, it will be seen that this construction will ensure that the shocks and stresses caused by the traffic will be transferred to the ballast so as to be dispersed over the greatest possible surface 10 and what is more essential that no unstressed portions or intervals will be left in the earth works between adjacent sleepers. According to the well known principle of engineering, it will be obvious that the forces 15 which will be transmitted by a sleeper having the elastic properties as herein disclosed, will be normal to the curvative thereof at any particular point. It will therefore be seen that theoretically the downward 20 forces transmitted to the earth works by a sleeper constructed as shown in Figs. 1 and 2 would begin just below the dot and dash line A—B (Fig. 1) and as indicated by the lines C in Fig. 2. Practically, however, 25 the theoretical reactions transmitted by the sleeper between the lines C and D, Fig. 2, may be disregarded as they would have but little or no deteriorating effect upon the earthworks because of the slight 30 degree of the deformations of the sleeper between these lines. Considering therefore those portions of the sleeper whose deformations are the greater and by which practically the full strength of the forces to which 35 the sleeper is subjected are transmitted to the earth works, it will be obvious that these forces are transmitted by those portions of the sleeper situated between the lines D and E in Fig. 2. With the sleepers spaced as 40 indicated diagrammatically in this figure it will be seen that the lines D intersect at the point F on the line G H so that therefore a continuous supporting area for the rails is formed along this line G H which 45 it will be noted is located quite close to the rails and that there are no unstressed portions along this area between the sleepers.

50 It will be noted that the gap 15 between the edges of the inclined portions 14 is very small so as to leave no unstressed portion upon the earth works and also to prevent the ballast from forcing its way upwardly into the interior of the sleeper, and 55 thus cause the interior of the sleeper to be filled up to such an extent that the under face of the top plane portion 10 would rest directly upon the ballast, and thus not only prevent the yielding effect of the sleeper, but by producing a pressure against the interior of the sleeper cause the gap 15 to be increased.

60 The sleeper is preferably provided as shown in Fig. 3 upon its upper portion 10 with one or more elongated slots 16 adjacent

the point where the rails are to rest and if desired this portion of the sleeper may be made of somewhat thicker construction than the other portions thereof, in order to compensate for the weakening of the structure 70 due to the presence of the slots 16.

After the sleepers have been placed in position and the rails attached thereto, ballast or soil is inserted into the interiors of the sleeper from the ends thereof, it being 75 understood that a space is left between the top portion 10 of the sleeper and the filling material to prevent a direct reaction between this top portion and the filling which as heretofore set forth would entirely destroy 80 the elastic effect of the sleeper. When the interiors of the sleepers are filled as described, it will be obvious that a considerable weight is represented by each sleeper which is of great value in securing 85 a substantial construction.

Having thus described my invention, what I claim as new and desire to secure by Letters Patent of the United States, is—

1. In a superstructure for railways, a 90 sleeper having a cross sectional profile consisting of a plane upper section to which the rail is attached, said upper section merging into arcuate side wall sections and said arcuate side wall sections merging into lower 95 plane sections extending tangentially from the lower ends of said sidewall sections and sloping downwardly, said lower plane sections having their outer ends free and terminating adjacent each other substantially 100 at the central line of said sleeper, said sleeper being supported by the ballast of the roadway entirely by said side wall and lower plane sections whereby said sleeper may yield elastically under the influence of downward forces and said forces will be transmitted and distributed by the elastic deformations of the lower portions of said arcuate side wall sections and inclined lower plane sections over a continuous supporting area situated a short distance below the rail.

2. A superstructure for railways as set forth in claim 1, in which said side wall sections consist of an arc of a circle of less than 180° in length and said lower plane sections are inclined downwardly from the termination of said side wall sections substantially at an inclination of 1:4 to the horizontal.

3. A superstructure as set forth in claim 1 in which means are provided to clamp the rail to said sleeper, said sleeper and means being provided with interengaging portions, whereby lateral shocks upon the rail are transmitted undiminished in strength to said sleeper.

In testimony whereof I have affixed my signature.

RICHARD SCHEIBE.
